FLOATING ROOF OR COVER FOR LIQUID STORAGE TANKS

John H. Wiggins, Chicago, Ill.

Application August 29, 1950, Serial No. 182,002

2 Claims. (Cl. 220—26)

1

This invention relates to floating tank roofs of the particular kind that comprise a flexible deck portion surrounded by and attached to a rigid, annular-shaped member that constitutes the peripheral portion of the roof, and which is of such weight that it exerts a sufficient downward force or load on the peripheral part of the flexible deck portion to maintain said deck portion in an inclined position, sloping upwardly from the periphery towards the center of the roof, whereby gases on the underside of the roof have a natural tendency to flow towards a gas collecting chamber or gas outlet at the center of the roof.

The main object of my present invention is to provide a floating roof of the general type or kind above mentioned, that is equipped with a novel means of inexpensive construction for accurately controlling the shape or form assumed by the flexible deck portion of the roof when the roof is floating.

Another object of my invention is to provide a floating roof of the general type or kind previously referred to, that is equipped with a flexible weather roof, which, in addition to preventing rain or snow, loads from collecting on the flexible deck portion of the roof, also effectively prevents said deck portion from assuming such a shape or form, when the roof is floating, that pockets of gas will be trapped on the underside of the roof at points between the periphery of the roof and the gas outlet or gas collecting chamber at the center of the roof. Other objects and desirable features of my invention will be hereinafter pointed out.

Figure 1 of the drawings is a fragmentary, vertical, transverse sectional view, showing my improved roof sustained by or resting upon the removable supporting structure inside of the tank on which the roof is built or fabricated;

Figure 2 is a similar view of a small size roof embodying my invention, showing the position assumed by the flexible weather roof and the flexible deck portion when the roof is not floating, but instead, is supported by brackets on the side wall of the tank;

Figure 3 is a similar view of a large size roof embodying my invention, showing the peripheral portion of the roof resting on supporting brackets on the tank side wall and the central portion of the roof resting on a stationary supporting structure located at the center of the tank; and

Figure 4 is a similar view, showing the normal condition of my improved roof, i. e., floating on and supported by a liquid or semi-liquid substance in the tank of the apparatus.

2

In the accompanying drawings which illustrate my invention embodied in a floating roof or cover for a sewage processing apparatus, A designates the side wall of a tank that is adapted to hold sewage or any liquid substance that is being stored or processed, B designates the flexible deck portion of my improved roof which is constructed of metal plates fabricated in such a manner as to produce a substantially flat, limber diaphragm that is capable of flexing throughout the major portion of its area, C designates as an entirety an annular member of rigid construction and of relatively great weight, that surrounds and is attached to the peripheral part of said flexible deck portion so as to force said peripheral part downwardly into the liquid a sufficient distance to normally maintain the deck in an inclined position sloping upwardly and inwardly from its inner edge when the roof is floating on the liquid, D designates a gas collecting chamber at the center of the roof, formed by a vertically-disposed, tubular member 1, that is closed at its upper end and open at its lower end, so as to permit gases on the underside of the roof to flow freely into the gas collecting chamber D, 2 designates a gas adhesion pipe leading out of said gas collecting chamber, and E designates a flexible weather roof arranged above the flexible deck portion B in spaced relation with same and attached at its outer and inner edges to the upper end of the annular, peripheral member C and to the upper end of the center tubular member 1, respectively. Instead of being provided with a center tubular member having a diameter such as to produce a gas collecting chamber of considerable volume, the roof may be provided with any kind of a suitable center support for the weather roof attached at its lower end to the flexible deck portion, and also may be provided with any kind of a gas outlet that permits the escape of gases from the underside of the flexible deck portion of the roof.

The basic idea of my present invention consists in using the weight or load of the flexible weather roof E to control the shape or form of the flexible deck portion B when the roof is floating on the liquid in the tank, as shown in Figure 4, and prevent pockets of gas from becoming trapped on the underside of the roof, at points between the periphery of the roof and the gas outlet at the center of the roof. I attain this result by arranging numerous vertically-disposed, rigid posts or thrust members F between the weather roof E and flexible deck portion B throughout the major area of said parts, as shown

in the drawings. As previously stated, my invention contemplates the use of a deck portion that is flexible and which is joined or attached at its periphery to a rigid, annular member or structure, which is of sufficient weight to create a relatively great downward force or load at the peripheral edge of said deck portion, for the purpose of maintaining said deck in an inclined position, sloping upwardly and inwardly towards the center of the roof, and thereby enhance or induce a flow of gases on the underside of the roof towards or into a gas outlet or gas collecting chamber in the roof. In other words, in such a roof it is essential for efficient operation, that the part of the flexible deck portion at the center of the roof be disposed in a higher horizontal plane than the peripheral part of said deck portion, and that the intermediate limber part of said deck portion lying between said two above mentioned parts be prevented from flexing upwardly and assuming such a shape or form as to trap pockets of gas or impede the flow of gases on the underside of the roof, towards the point where gases are intended to be collected or released from the underside of the roof. In my improved roof, the previously mentioned rigid posts or thrust members F cause the weight or load of the weather roof E to be applied to or exerted downwardly on the limber metal diaphragm which constitutes the flexible deck portion B at enough points throughout the area of said deck portion, to counteract the tendency of said limber metal diaphragm to flex into such a shape or form, as to trap pockets of gas, thereby insuring that the deck portion B of the roof, when the roof is floating, will be maintained in its predetermined shape or form shown in Figure 4. In addition to controlling the shape or form of the flexible deck portion of the roof, the posts or thrust members F also maintain the flexible weather roof E in an outwardly and downwardly-inclined position that insures efficient drainage of same. Any upward flexing of the deck portion B, produced by the great uplift force of the buoyant liquid or gases contacted by said deck portion, enhances the drainage characteristics of the weather roof and also increases the load that is relied upon to assist in maintaining the predetermined shape or form of the flexible deck portion, due to the fact that upward flexing of said deck portion is transmitted by the posts F directly to the flexible weather roof E in a direction tending to flex the same and lift the annular peripheral portion C of the roof to which the periphery of the weather roof is attached. Normally, the posts or thrust members F will be tack-welded to the flexible deck portion B and weather roof E, because said deck portion and weather roof will bend locally enough to take care of the relative rocking movement between said thrust members and the two elements of the structure between which they are interposed, but, if desired, the weather roof and flexible deck portion can be provided with lugs joined by pivot pins to the upper and lower ends of the thrust members F.

The rigid, annular, peripheral portion C of the roof to which the peripheries of the weather roof E and deck portion B are attached, can be constructed in various ways without departing from the spirit of my invention. It may consist of an annular rim 3 welded to the peripheral edges of said weather roof and deck portion and combined with a built-in load member 4 of concrete or the like that is cast or molded in situ onto said rim

3 and interlocked with same by anchoring devices 5, or said peripheral portion C may comprise an additional annular rim 3a arranged in concentric relation with the rim 3 on the interior of same and interlocked with the load member 4, said additional rim 3a being attached to the peripheral part of the flexible deck portion B and being utilized as a form member in the operation of casting or molding the concrete or other pourable material, that is employed to add weight and impart rigidity to the peripheral portion C of the roof.

The roof is built or fabricated on a removable supporting structure inside of the tank that is shown in broken lines in Figure 1. If the roof is of relatively small diameter, it may be supported by brackets 6 on the tank side wall when it is not floating, as shown in Figure 2, as the flexibility of the deck portion B and weather roof E permit the central portion of the roof to sag. If desired, drains 7 can be built into the roof, as shown in Figure 2, so as to carry rain water off the low point of the weather roof when the roof is supported by the side wall brackets 6. In a roof of relatively great diameter, as shown in Figure 3, it is preferable to support the roof, when it is not floating on liquid in the tank, by supporting brackets 6 on the tank side wall on which the peripheral portion of the roof rests, and a stationary supporting structure 6a in the tank on which the central portion of the roof rests.

Having thus described my invention, what I claim as new and desire to secure by Letters Patent is:

35. 1. A floating roof for liquid storage tanks, comprising a flexible deck portion formed by a substantially flat, limber diaphragm that floats on the liquid in the tank, a vertically-disposed, tubular member at the center of the roof attached to said deck portion and being open at its lower end so that gases on the underside of the deck portion can escape upwardly into said tubular member, an upwardly-projecting rim at the peripheral edge of said deck portion interlocked with a rigid, annular load member formed of concrete or the like that is cast or molded on said rim so as to sink the peripheral portion of the roof into the buoyant liquid a sufficient distance to cause said deck portion to normally assume an inclined position sloping upwardly and inwardly towards the center of the roof, a flexible weather roof attached to the upper end of said rim and to the upper end of the tubular member at the center of the roof and disposed so as to prevent rain, snow and the like from falling on said deck portion, and vertically-disposed, rigid thrust members interposed between the deck portion and the weather roof so as to utilize the weight of the roof to maintain said deck portion in a predetermined shape or form.
55. 2. A floating roof for liquid storage tanks, comprising a flexible deck portion formed by a substantially flat, limber metal diaphragm of circular form, an annular member surrounding and attached to said deck portion, said annular member being of such weight as to cause said deck portion to assume an inclined position, sloping upwardly and inwardly from the periphery towards the center of the roof, a gas outlet leading from approximately the center of the underside of said deck portion, a flexible weather roof arranged over said deck portion and attached at its periphery and center to parts carried by said deck portion, said weather roof being inclined downwardly and outwardly from its center to

wards its peripheral edge for the purpose described, and vertically-disposed, rigid posts interposed between said deck portion and weather roof for supporting said weather roof and using the weight or load of same to resist upward flexing of said deck portion, the said annular member having a built-in load element constructed of concrete or the like, that is cast in situ and interlocked with said annular member.
